Jared Byington
Letters Patent

The Schedule referred to in these Letters Patent
of Making part of the same containing a descrip-
tion in the words of the said Jared Byington himself
of his improvement in manufacturing Pitch Forks

The characteristic principle in what
is usually called by Mechanics a spring temper
or that temper given to steel proper for spring-
is some locks, steel traps &c applied to Pitchforks,
which may be done in the following manner viz

Ih. forks being made with two or more
prongs each of which may be made round, four
or eight square or any shape that may suit
the workmen & steel or such other substance
as will admit of a spring temper —

It is to be tempered in the following
manner, the fork is to be heated red hot or
such heat as is proper for the temper of the steel
& plunge it into water or some other liquid proper
to harden it & if need be reduce the temper by
heating the fork until it is brought to a proper
temper for springs — then if the workman choo-
ses some kind of oil or grease with about one
twelfth part of the spirits of turpentine mixed
together may be applied to the fork while hot
to toughen the steel.
